UNITED STATES PATENT OFFICE.

ISAAC UNGER, OF GREENVILLE, OHIO.

MAIL-BOX CARRIER.

SPECIFICATION forming part of Letters Patent No. 722,929, dated March 17, 1903.

Application filed May 12, 1902. Serial No. 106,936. (No model.)

To all whom it may concern:

Be it known that I, ISAAC UNGER, a citizen of the United States, residing at Greenville, in the county of Darke and State of Ohio, 5 have invented a new and useful Mail-Box Carrier, of which the following is a specification.

This invention is intended for use more particularly in connection with the "rural 10 free-mail-delivery system" where the house to which the mail is addressed is distant from the road to enable the residents to convey the mail to and from a point of delivery at the line of the road, and thus obviate the necessity for the mail-carrier leaving his route 15 in delivering or receiving the mail.

The device may also be employed for conveying other matter than "mail" and for other purposes than in connection with the 20 rural free-delivery system, but is more particularly designed for the purposes above indicated.

In the drawings illustrative of the invention, Figure 1 is a side elevation with the central portions broken out to economize space. Fig. 2 is an enlarged detail of the carrier-receptacle at one of the intermediate supporting-posts. Fig. 3 represents an enlarged sectional view of the standard to which the cable ends are attached. Fig. 4 represents another sectional view thereof, showing the cable-carrying drum mounted thereon. Fig. 5 represents a plan view of a portion of the carrier, showing the mail-receptacle in position near the supporting-pulleys. Fig. 6 represents a detail view showing the means for locking the drum against backward movement.

The device may be erected between comparatively 40 distant points, and in the illustration shown in Fig. 1 the terminals are represented at 10 and 11, respectively, the former indicating the point where the mail is to be delivered, such as the residence to which 45 the mail is addressed, and the latter the point on the mail-route where the carrier deposits the mail. The terminals will be connected by a guide or trolley wire 12, which is supported at suitable intermediate points by 50 posts 13, having U-shaped hangers 14 engaging the guide-wire, as shown. At the residence end a cable-pulley 15 is connected, as

by a bracket 15^a, and at the deposit end another similar pulley 16 is similarly supported by a bracket 16^a, the bracket in the latter case 55 being preferably carried by a vertical bar 17 upon a post 18. Over the pulleys 15 16 a cable 19 is carried, as shown, the adjacent ends of the cable being united to a standard 20. This standard 20 is bifurcated at its lower end, and 60 the members thereof curve outwardly in opposite directions, as at 20^a 20^b, and are provided with grooves to receive the adjacent ends of the cable, which are carried upward through openings in the standard and engaged 65 to a drum 21 upon the standard, as shown. The grooved bifurcated lower end of the standard holds the cable ends out of contact with each other and prevents friction. The upper end of this standard 20 is also bifurcated, and 70 the two members 20^c and 20^d are spaced apart and offset to form bearing for the drum 21. The drum 21 will be provided with a ratchet 22, with which a pawl 23 on the standard 20 engages. The shaft 21', on which the drum 75 is mounted, is extended through the arm 20^c in the form of an angular stem 21" for engagement by a suitable tool or handle for rotating the drum and regulating the tension of the cable. By this simple means the cable may be stretched to any required extent 80 and maintained at any desired tension by merely revolving the drum 21.

Attached to the standard 20 is a laterally-extended frame 24, carrying traveler pulleys 85 or trolleys 25 25^a, which engage the trolley-wire 12, as shown. The mail-receptacle is suspended from this frame 24, the receptacle being indicated at 26 and connected to the frame by reversely-diagonal hanger-bars 27 90 27^a, preferably curving inward, as shown, so that the center of gravity of the receptacle will be in substantial vertical alinement with the trolley-wire to obviate side strains.

Supported within the hangers 14 are supporting-pulleys 28 28^a, over which the two parts of the cable are carried in opposite directions as the cable is operated. The long distances apart of the supporting-posts 13 enable the guide-pulleys 28 28^a to be placed side 100 by side, as indicated, without danger of the side draft causing them to "ride" the pulleys and run off from them. The pulley 15 will be provided with a crank 15^b or other

means by which the cable 19 may be operated. By this simple means the mail may be conveyed to and from the route of the mail-carrier any desired distance and the work of the carrier thereby greatly lessened, as by this simple device there will be no necessity for him to take time to leave the route to deliver mail to distant residences.

The cable 19 may be of any size to adapt it to the distance traveled and may be either one strand of wire or several strands twisted into a cable or formed of any other suitable material.

The device may be readily adapted to any irregularity of the ground over which it is carried and may be modified and altered in minor particulars without departing from the spirit of the invention or sacrificing any of its advantages.

Having thus described my invention, what I claim is—

1. In a device of the class described, a trolley-wire supported between terminals, cable-pulleys disposed at said terminals, a trolley with wheels engaging said trolley-wire, a cable engaging said pulleys, and a single drum mounted upon said trolley upon which both the ends of said cable are wound in the same direction to regulate the tension of said cable.
2. In a device of the character described, a trolley-wire supported between terminals, cable-pulleys disposed at said terminals, a cable engaging said pulleys, a standard engaging the adjacent ends of said cable, means carried by said standard for adjusting the tension of said cable, and trolley-wheels supported from said standard and engaging said trolley-wire, substantially as described.
3. In a device of the character described, a trolley-wire supported between terminals, cable-pulleys disposed at said terminals, a cable engaging said pulleys, a standard having bifurcated upper and lower ends, the upper ends being spaced apart and offset, a drum mounted between said offset ends and con-

nected with the ends of the cable, means for revolving the drum, and trolley-wheels carried by said standard for engaging the trolley-wire.

4. In a device of the character described, a trolley-wire supported between terminals, cable-pulleys supported at said terminals, a cable engaging said pulleys, a standard carrying trolley-wheels engaging said trolley-wire, a drum carried by said standard and adapted to receive the ends of said cable, means for revolving said drum, and means for locking said drum from backward movement, substantially as described. 55

5. In a device of the character described, a trolley-wire supported between terminals, cable-pulleys disposed at said terminals, a standard having grooved diverging lower portion adapted to receive the ends of said cable, means carried by said standard for adjusting the tension of said cable, and trolley-wheels carried by said standard and engaging said trolley-wire, substantially as described. 60

6. In a carrier having a cable guided over terminal end pulleys, means for connecting the ends of said cable consisting of a vertically-perforated standard bifurcated to form curved guides for the cable ends, and having means for securing, and adjusting the strain upon the latter. 70

7. In a device of the character described, a cable guided over pulleys at the terminal ends, means for connecting the ends of, and adjusting the strain upon the cable, a carrier, means for supporting said carrier, and connecting means between said carrier and the device connecting the ends of the cable. 75

In testimony that I claim the foregoing as my own I have hereto affixed my signature in the presence of two witnesses.

ISAAC UNGER.
